UNITED STATES PATENT OFFICE

168,516

TABLE AND CHAIR COMBINATION

Edward W. Long, Flagler, Colo.

Application April 2, 1951, Serial No. 14,688

Term of patent 3½ years

(Cl. D33—14)

To all whom it may concern:

Be it known that I, Edward W. Long, a citizen of the United States, residing at Flagler, Kit Carson County, State of Colorado, have invented a new, original, and ornamental Design for Table and Chair Combination, of which the following is a specification, reference being had to the accompanying drawing, forming a part hereof.

Figure 1 is a side elevation of a table and chair combination, embodying my new design.

Fig. 2 is a front elevation of the design shown at Fig. 1.

Figure 3 is a plan of the design shown at Figs. 1 and 2.

Figure 4 is a sectional view taken on line 4—4 of Fig. 2.

I claim:

The ornamental design for a table and chair combination, as shown.

EDWARD W. LONG.
